IMPRESSION COATING MACHINE

Fay D. Kinney, Southbridge, Mass., assignor to
United Shoe Machinery Corporation, Paterson, N. J., a corporation of New Jersey

Application June 29, 1929. Serial No. 374,693

15 Claims. (Cl. 91—47)

This invention relates to machines for coating defined areas of sheet material with paste, cement, solvent or other medium. It may be utilized with particular advantage in the manufacture of boots and shoes for coating shoe parts with paste, and under the term paste I include broadly all types of liquid adhesive.

In the manufacture of rubber-soled shoes, it is the practice to apply a coating of rubber cement to the margin of the vamp in a defined band or zone extending about the forepart thereof. The location and boundary of such zone of cement must be determined with extreme accuracy for if any portion thereof shows in the finished shoe 15 above the line of the foxing, the shoe is regarded as a second and cannot be disposed of at full price. It is equally important to ensure uniform distribution of the cement within the limits of the desired zone as otherwise it is impossible to 20 secure complete vulcanization of the sole and upper. One important field of use of my invention is the handling of such work although its application is not limited to this or to any particular type of work.

25 In one aspect, my invention consists in a machine having a work support and a presser plate relatively movable to engage and flatten a piece of sheet material, such as a shoe part, associated with a member having a paste-applying face of defined area movable through a slot in the presser plate to apply its charge of paste in a zone of correspondingly defined area to the accurately located and flattened work piece. The work may be thus positioned with a high degree of accuracy 30 and maintained in the most favorable condition for the reception of the paste while the paste is delivered in a uniformly distributed zone of sharp well-defined outline.

35 Among other features, I provide a novel work support employing suction openings for holding the work in place after it has been accurately located thereon, thus preventing inaccuracies due to displacement of the work.

The paste-applying mechanism includes a detachable and replaceable member having a paste-applying face of defined area, and this is preferably bounded by ribs which limit the applied paste to a zone of clean-cut outline. In supplying paste to the applying member, I preferably 40 utilize a transferring roll which is bodily movable across the face of the applying member and driven in a direction reverse to the direction in which it would be turned by rolling contact with the applying member during its travel across said member. This construction ensures the delivery

of an excess amount of paste to the applying member which may be reduced subsequently as desired without danger of leaving bare spots. The advantageous uniform distribution of paste within the limits of its zone is thus reliably 60 effected.

These and other features of the invention will be best understood and appreciated from the following description of a preferred embodiment thereof, selected for purposes of illustration and shown in the accompanying drawings, in which

Fig. 1 is a view of the machine in side elevation;

Fig. 2 is a plan view of the carrier of the paste-applying member;

Fig. 3 is a view of the machine in front elevation, with certain parts shown in section;

Fig. 4 is a sectional view on the line 4—4 of Fig. 3;

Fig. 5 is a plan view of a portion of the work 75 support;

Fig. 6 is a detail sectional view of one of the gauges; and

Fig. 7 is a view in perspective of the paste-applying member.

The invention is herein shown as embodied in a molding or pressing machine of well-known type, comprising a frame 10, stationary side rods 12 carrying a stationary cross head 14 and guiding a vertically moving cross head 16 which is raised and lowered by the action of toggle links, 85 a portion of one link 18 being shown in Fig. 3.

The movable cross head 16 is shown in its lower position in Figs. 1 and 3, where it is maintained at rest when the machine comes to rest. In this initial position it affords the operator free and unobstructed access to the platen 19 which it carries, for the purpose of removing the coated work and for presenting and locating a fresh piece in 90 position to be coated.

The platen or work support 19 carried by the movable cross head 16 includes a suction chamber 24 surrounded by an outer wall and covered by a perforated top plate 22 which supports a covering 20 of yielding material, such as fibre or rubber, upon which the work is directly placed. Perforations 26 extend through the covering 20 and the plate 22 and constitute suction openings by which the work is held in position upon the platen during the paste-applying operation.

At its rear side, the suction chamber 24 communicates with an exhaust pipe 28 (Fig. 1) through a valve 30 which is operated automatically to cut off the suction when the cross head 16 is moved into its lowermost position and to

establish the suction connection when this cross head is elevated toward its operative position. To this end, an operating rod 32 is connected to the valve arm and is arranged to bear against a stationary portion 33 of the machine frame when the crosshead 16 is in its lower position. The rod is provided with a collar 36 upon which acts a compression spring 34, positioned between said collar and a bracket 37 attached to the head 16 and tending always to hold the lower end of the rod 32 in contact with the frame. When the cross head 16 is elevated, the rod 32 drops under the impulse of the spring 34 until stopped by contact of a collar 35 with the bracket 37, swinging the valve in an anti-clockwise direction and opening the connection so that the work will be held in place by suction throughout the movement of the cross head.

The platen is provided with suitable gauge pins 38 to assist the operator in accurately locating the work thereon. Each of the gauge pins is mounted in a casing 40 and is backed up by a compression spring, allowing the gauge to retract when it encounters the overhead presser plate but maintaining it in elevated position, as shown in Fig. 6, while the cross head occupies its lower or work-receiving position. The gauge pins are shown in Fig. 5 as located to position a vamp by reference to its longitudinal axis, the vamp being indicated in dotted lines. It will be apparent, however, that the platen may be equipped with additional gauge pins, located at appropriate points, for positioning work pieces of any desired shape or size.

The paste-applying mechanism is mounted upon the upper stationary cross head 14 in a frame which comprises a plate 42, to which is bolted a pair of side plates 44, and the flange 50 of a stationary, centrally-located post 52. The post 52 has a collar 62 secured thereto and is surrounded by a cylindrical sleeve 58 having a circular flange 66 formed integral with its lower end. The sleeve 58 is spaced from the post 52 by the stationary collar 62 and by an inwardly extending circular flange formed at the upper end of the sleeve, and in the chamber thus formed is located a compression spring 60 which tends at all times to hold the sleeve 58 in its uppermost position and in contact with the flange 50. The lower end of the post 52 is slotted to receive a pin 64 which extends between the sides of the sleeve 58 and is flattened to move vertically in the slot 59 in the post 52 when the sleeve 58 is forced downwardly against the compression of the spring 60.

Secured to the flange 66 of the sleeve 58 is a slotted ring 68 which constitutes the carrier for the paste-applying member. The paste-applying member comprises a continuous curved bar 70 having a pair of marginal ridges or ribs 72 (Fig. 7) bounding its lower or paste-applying face and with its intermediate surface corrugated, as shown in Fig. 7. A series of screws are threaded into the upper face of the bar 70 and extend through approximately radially positioned undercut slots 69 in the carrier ring 68, as shown in Fig. 2. The bar 70 is, therefore, securely mounted upon its carrier ring 68 and it will be apparent that other bars of different contour may be conveniently substituted by being placed beneath the slots 69 and drilled for the reception of attaching screws.

The lower end of the post 52 is reduced to receive a disk-shaped head 54 which fits within the bore of the sleeve 58 and carries a stationary work-engaging or presser plate 48 brazed or oth-

erwise secured thereto. This plate 48 is reinforced and supported about its edges against upward pressure by a filler plate 46 secured by brazing, or in any other suitable manner, to the lower edges of the side plates 44, above referred to. The presser plate 48 is slotted to receive the paste-applying bar 70, as shown in Figs. 3 and 4. The parts are so arranged and proportioned that normally the tops, here the lower faces of the limiting ribs 72 of the paste-applying bar, are flush with the lower surface of the presser plate 48 as shown in Fig. 3. When the sleeve 58 is depressed, the bar 70 is moved downwardly and protrudes through the slot in the presser plate and in this position engages the surface of the work and deposits its charge of paste thereon, as will presently appear.

Paste is delivered to the operative face of the bar 70 by a roller 96, mounted upon a transverse shaft 94 in a paste receptacle 76. The paste receptacle is provided at its corners with upwardly-extending arms 78, each of which carries a short shaft 86 having secured thereto a roller 80 and a pinion 82. The rollers 80 run upon tracks formed in the outer faces of the side plates 44 and constitute trucks for carrying the receptacle 76 back and forth in a horizontal path beneath the presser plate 48. The receptacle is provided with a wire bail 77 (Fig. 1) extending forwardly and across the front of the machine head, which the operator may grasp in effecting the movement of the receptacle. The pinions 82 mesh with racks 74 secured to the side plates 44 adjacent to the tracks for the rollers. One of the rearmost studs 86 carries at its outer end a sprocket wheel 88, upon which runs a sprocket chain 90 which drives a smaller sprocket wheel 92 upon the shaft 94 of the paste-applying roller 96. This roller 96 is thus rotated reversely to the direction in which it would be turned by rolling contact with the presser plate 48 during its travel across the bar 70 and at a fairly high linear speed, so that the upper surface of the roller 96 wipes over the bar 70 and acts to supply an excess amount of paste to the surface of that bar.

The receptacle 76 contains also a scraper 99 comprising a transverse plate or blade carried between the forwardly-extending arms of a pair of bell crank levers 98 (Fig. 1) pivotally mounted within the receptacle and normally urged in an anti-clockwise direction by tension springs 95, so as to maintain the scraper yieldingly against the lower face of the stationary presser plate 48. When the receptacle is pulled forwardly by the operator, the paste-carrying face of the bar 70 is filled with paste by the action of the roller 96 and the face of the presser plate 48 is more or less coated at the same time. When the receptacle is moved rearwardly, the scraper 99 acts to clean the face of the presser plate and remove all paste except that retained between the marginal ribs of the paste-applying member 70.

In order to cause the paste-applying bar to protrude through the presser plate 48, a hand lever 61 is pivotally mounted upon a bracket 63 on the stationary cross head and connected to a downwardly-extending rod 65 which passes through a central bore within the post 52 and engages the cross pin 64 which is set in the sleeve 58 and slides in the slot 59 of the post 52. When, therefore, the operator depresses the hand lever 61, the sleeve 58 is lowered and the paste-applying bar projected downwardly beyond the surface of the presser plate 48.

In using the machine herein disclosed for ap-

plying a band or zone of paste to a vamp such as that illustrated in Fig. 5, the operator positions the vamp in flat condition upon the platen with the assistance of the gauge pins 38 while the cross-head is in its lower position, as shown in Fig. 1. He then moves the paste receptacle forwardly and rearwardly, delivering a charge of paste to the paste-applying bar 70. The machine is then started, whereupon the lower cross head is elevated to a position in which the work is located close to or in touch with the presser plate 48, which tends to flatten the work and remove any wrinkles that may occur in it. The machine comes to rest in this position, whereupon the operator swings the hand lever 61, forcing the paste-applying bar 70 downwardly and into contact with the surface of the work. As the latter is supported in a yielding manner, a perfect contact is secured throughout the extent of the paste-applying member and substantially all of the paste on the bar is transferred to the surface of the vamp in a definite curved zone determined accurately by the limiting ridges 72 of the bar because of the greater adhesion of the paste to the work than to the metal bar 70. The lever 61 is then released and the machine started again to return the platen and the coated work to initial position.

It will be understood that the illustrated machine is adapted to be interchangeably equipped with paste-applying members of any desired outline and with correspondingly slotted presser plates. The curved V-shaped bar 70 is illustrated merely as an example of the type of paste-applying member useful in the operation of cementing vamps and its design is, therefore, of secondary importance.

Having thus described my invention, what I claim as new and desire to secure by Letters Patent is:

1. A machine of the class described, having in combination, a support movably mounted in the machine to carry the work into paste-receiving position, and a recessed paste-applying member having a paste-carrying face bounded by spaced marginal ribs disposed in a plane parallel to said support and arranged to engage the work and apply paste thereto in a defined zone.

2. A machine of the class described, having in combination, a movable work support, means for moving said support to carry the work into paste-receiving position, and a normally inverted recessed paste-applying member having spaced marginal ribs limiting an elongated paste-carrying face on which a charge of paste is carried, said member being arranged to engage the work and deposit the charge of paste thereon in a zone defined by said marginal ribs, said work-support-moving means acting to raise the work into contact with the inverted paste-applying member.

3. A machine of the class described, having in combination, a work support and a paste-applying member of defined area arranged for relative movement to effect the application of paste to the work, and a paste-supplying roll movable forward across the face of said applying member and being rotated to move the contacting face of the roll in the direction of forward travel.

4. A machine of the class described, having in combination, a work support and a recessed paste-applying member of defined area arranged for relative movement to effect the application of paste to the work, a paste-supplying roll movable forward across the recessed face of said applying member, and means for rotating said roll in a

direction reverse to that which would be imparted by simple rolling contact and at such linear speed as to deliver an excess of paste to said recessed member.

5. A machine of the class described, having in combination, a presser plate and work support relatively movable to engage opposite sides of and to clamp the work and to come to rest in such position, said presser plate having a cut-out portion, and a paste-applying member of defined area movable in said cut-out portion to apply paste in a zone of corresponding shape to the work while so engaged. 80

6. A machine of the class described, having in combination, a presser plate and a work support relatively movable to engage the work, said presser plate having a curved slot therein, means for positioning a vamp on the work support in predetermined relation to said slot, and a curved elongated paste-applying member movable through the slot to apply paste in a defined curved zone to the vamp while so engaged. 90

7. A machine of the class described, having in combination, a presser plate having a slot, a paste applying member having a ribbed face the tops of the ribs of which are initially disposed flush with said plate, a paste-supplying roll movable across said presser plate and applying member to coat both, filling the spaces between the ribs of said applying member, and a scraper movable across said plate and applying member to clean the face of the plate and level the paste upon the paste-applying member. 100

8. A machine of the class described, having in combination, a work support, a cooperating presser plate having a slot, a paste-applying member having spaced marginal ribs located flush with said plate and defining a paste-supplying face, a paste-supplying roll movable across said plate and applying member, and a scraper arranged to follow said roll to clean the presser plate while leaving a charge of paste between the ribs of the paste-applying member. 110

9. A machine of the class described, having in combination, a work support and paste-applying mechanism relatively movable toward and from each other, a suction chamber associated with the work support and means responsive to said relative movement arranged automatically to render operative said suction chamber to hold the work in position on the support during such relative movement. 120

10. A machine of the class described, having in combination, a work support and paste-applying mechanism relatively movable from separated work-receiving position to adjacent paste-applying position, suction means associated with the work support, being shut off to permit the work to be freely positioned upon the work support in the separated position thereof, and means for automatically rendering the suction effective as the work support approaches paste-applying position. 130

11. A machine of the class described, having in combination, a work support and a presser plate movable to engage and flatten a piece of sheet material over substantially its entire area, said presser plate having a slot in its surface, and a paste-applying member movable through the slot into engagement with the work to place a defined zone of paste thereon. 140

12. A machine of the class described, having in combination, a work support, and paste-applying mechanism including a yieldingly mounted flanged sleeve, a slotted ring secured to the flange of the sleeve, and a curved bar detachably se- 150

- cured to said slotted ring and having a paste-applying face of defined area.
13. A machine of the class described, having in combination, a work support, and paste-applying mechanism including a stationary slotted post, a sleeve yieldingly mounted thereon and having a cross pin extending through the slot in the post, a paste-applying member of defined area carried by the sleeve, and means acting axially 10 of the post upon said cross pin to move the sleeve and its associated paste-applying member toward the work support.
14. A machine of the class described, having in combination, a work support, a presser plate, a member associated therewith having a paste-applying face of defined area, a paste container hav-
- ing a transferring roll movable bodily across the face of said presser plate and said applying member, means for rotating the roll to cause its periphery to wipe over the applying member, and means for scraping the face of the presser plate. 80
15. A machine of the class described, having in combination, a vertically movable head having a work support, and a stationary head having paste-applying mechanism including a post carrying a yieldingly mounted member having a 85 defined paste-containing face, a carriage movable transversely across said face and having a paste container and a transferring roll, and means for positively driving said roll when the carriage is reciprocated. 90
